(57) **CLAIM**

The ornamental design for an electric connection unit, as shown and described.

DESCRIPTION

FIG. 1 illustrates a perspective view of an electric connection unit showing the design.

FIG. 2 illustrates a front view of the electric connection unit.

FIG. 3 illustrates a rear view of the electric connection unit.

FIG. 4 illustrates a left side elevational view of the electric connection unit.

FIG. 5 illustrates a right side elevational view of the electric connection unit.

FIG. 6 illustrates a top plan view of the electric connection unit; and,

FIG. 7 illustrates a bottom plan view of the electric connection unit.

The broken lines in the drawings depict portions of the electric connection unit that form no part of the claimed design.
